CLAIM

(21) Appl. No.: **29/474,264**

I claim the ornamental design for the passive acoustic amplifier for multi-media devices, as shown and described.

(22) Filed: **Jul. 25, 2014**

DESCRIPTION

(51) **LOC (10) Cl.** **14-03**

FIG. 1 is a perspective view of a passive acoustic amplifier for a multi-media device showing my new design;

(52) **U.S. Cl.**

FIG. 2 is a front view thereof;

USPC **D14/188; D14/253**

FIG. 3 is a back view thereof;

(58) **Field of Classification Search**

FIG. 4 is a right-side view with the left side being a mirror image thereof;

USPC D14/188-198, 204, 208, 209.1,
D14/215-216, 224-224.1, 243, 251-253;

FIG. 5 is a top view thereof;

181/177, 179; 381/120

FIG. 6 is a bottom view thereof;

CPC H04M 1/04

FIG. 7 is a front view, identical to FIG. 2, with an additional broken line rectangle representing a multi-media device in a upright or vertical position placed on the device and is for illustrative purposes only; and,

See application file for complete search history.

FIG. 8 is a front view, identical to FIG. 2, with an additional broken line rectangle representing a multi-media device in a horizon position placed on the device and is for illustrative purposes only.
